CLAVICLE SPLINT

Fred William Peterson, El Centro, Calif., and
Otto S. Kirschner, Vashon, Wash.

Application August 16, 1946, Serial No. 690,854

3 Claims. (Cl. 128—87)

1

Our invention relates to appliances used for the reduction of fractures of the collar bone or clavicle.

Objects of the invention are: to provide a clavicle splint that is not bulky, is light in weight, and has no protruding rigid members to interfere with the patient's lying in almost any position; to provide a splint so designed and constructed that the patient may wear ordinary clothing over the splint during convalescence; to provide a splint which can be so manipulated and adjusted that the upward, outward, and backward movements can be effected and the up, out, and back position maintained; to provide a splint which employs the uninjured shoulder as a means of counter pressure to bring to bear pressure in an outward direction to the injured side; and to provide a splint whose metal parts are sufficiently rigid to maintain the position desired, yet are sufficiently flexible to permit forming them by hand to fit the various shapes of individual chests and shoulders.

Other objects will in part be obvious and in part will be pointed out hereinafter.

To the attainment of the aforesaid objects and ends, the invention further resides in the novel details of construction, combination and arrangement of parts, all of which will first be described in detail and then be specifically pointed out in the appended claims, reference being had to the accompanying drawing in which—

Fig. 1 is a front view showing the application of our invention to a patient.

Fig. 2 is a back view of the same.

Fig. 3 is an enlarged detail front elevation of a portion of the appliance, strap parts being broken away.

Fig. 4 is a further enlarged detail view of a four-buckle unit used to connect the shoulder straps and belt strap at the back of the patient.

Fig. 5 is a side elevation, parts being broken away, on a small scale.

In the drawing, in which like numerals of reference indicate like parts in all the figures, 1 represents the central connecting plate to which the arms or diagonal flat rods 3 are pivoted at 4 thereby forming what we term a V. The plate 1 has a vertical slot-forming loop 2 through which a chest strap 24 passes.

The upper ends of the flat rods 3 are pivoted at 8 to the arcuate bars 5 which are padded into approximately tubular form or circular-cross-section by means of leather covered foam rubber pads 6, laced into place as at 7 to facilitate removal and replacement when soiled. At

2

5 the lower portions of the bars 3, loops 9 are pivoted as at 10. The shoulder straps 11 are secured to these loops. Straps 12 are secured to the lower ends of the padded bars 5 while short straps 13 are secured to the upper ends of the same, the short straps being provided with buckles 14. A back strap 15 is secured to one of the short straps 13 while a short back strap 16 is secured to the other short strap 13 and is provided with a buckle 17. The straps 12 co-operate with the respective buckles 14 while strap 15 cooperates with buckle 17.

10 18 is a triangular ring to two sides of which short straps 22 are secured. Buckles 23 are secured to the respective short straps 22 to receive the ends of the chest strap 24. A strap 19 passes through the ring 18 and engages the third side and has buckles 21 secured to its ends. A connecting strap 20 keeps the strap 19 from becoming detached from the ring 18 while permitting limited longitudinal movement to be given to the strap 19. The free ends of straps 11 cooperate with the buckles 21 respectively.

15 While the means for effecting the backward movement of the distal fragment of the clavicle is of the standard design of a strap and engaging buckle across the back of the shoulder, the mechanism to effect the upward and outward movements is novel and unique in our appliance. By 20 raising the apex of the expanding V, after pulling the shoulder back with the strap 15 across the shoulder blades, the distal ends of the V members 3, with their attached, padded circular elements engaging the ball of the shoulder and the 25 underarm, the distal end of the fractured clavicle is moved upward and outward, and by buckling the two straps 11 which lead from the apex of the V up and over the proximal fragment to a junction of the strap 24 which girdles the chest 30 at a point over the spine just below and between the lower edges of the scapulae, the up and out position is maintained. Stated in simple terms by cinching up on the four buckles 21, 21, 23, 23 35 in the center of the back, the ball of the shoulder and its attached distal fragment of the clavicle are moved upward and outward and rigidly held in this position. Simultaneously, the proximal fragment is depressed by the strap which passes over it, thus holding the two fragments in alignment. Another novel feature of our splint lies 40 in the fact that it employs the uninjured shoulder as a means of counter pressure to bring to bear pressure in an outward direction on the injured side. The design of the splint is novel also in 45 that it employs a longitudinal slot in or on the

central connecting member 1 of the V to permit the apex of the V to be moved upward without moving the strap which encircles the chest. This is an important feature in applying the splint to a female patient, where the body strap encircles the thorax just below the breasts.

In our splint the weight of the distal fragment and the arm is supported by the padded axillary member (5, 6, 7), which in turn is supported by one of the arms of the V. This again is supported by the shoulder strap passing over the proximal fragment of the broken clavicle. Accordingly, the problem of elevating the distal fragment into alignment with the proximal fragment is solved by a proper cinching of the shoulder strap to the point where the downward pressure on the proximal fragment just balances the lifting impetus of the axillary member supporting the distal fragment.

In as much as all of the supporting members of the splint bear only upon the shoulder girdle and the upper part of the thorax, flexing, bending, stooping, or twisting at the waist or hips do not alter the position of the skeletal parts of the shoulder girdle. In other words, only the shoulder girdle is immobilized, adding greatly to the comfort of the patient.

From the foregoing description taken in connection with the accompanying drawing it is thought that the construction, operation and advantages of our invention will be clear to those skilled in the art.

What we claim is:

1. A clavicle splint comprising a front connecting plate; a right and a left rod pivoted at one end of each to said plate and diverging upwardly forming a V; right and left shoulder straps anchored, one to each said rod adjacent the pivoted ends of the same; padded arcuate bars pivoted to the other ends of said rods; adjustable straps secured to the free ends of each said padded arcuate bars; an adjustable back strap connecting the upper ends of said padded arcuate bars; a chest strap engaging said front connecting plate; a back unit having connected buckle straps provided with four buckles with two of which said chest strap connects and with the other two of which said shoulder straps respectively connect.

2. A clavicle splint comprising a vertical front connecting member having a vertically elongated slot-like portion; a chest strap passing freely through said slot-like portion and being of less width than the length of said slot-like portion;

a right and a left flat rod separately pivoted to said front connecting member adjacent the upper end of the same; padded arcuate members pivotally connected to the free ends of said right and left rods and engaging the ball of the shoulder and under the arm; adjustable straps connecting the free ends of said arcuate members; right and left shoulder straps pivotally connected respectively to said right and left rods; a back cross strap adjustably connecting the upper ends of said arcuate members; and a connecting unit comprising a triangular ring, a strap having a buckle at each end and slidably connected to one side of said ring and cooperating with said shoulder straps, straps with buckles secured to the other sides of said ring to cooperate with the respective ends of said chest strap.

3. A clavicle splint comprising a vertical front connecting member having a vertically elongated slot-like portion; a chest strap passing freely through said slot-like portion and being of less width than the length of said slot-like portion; a right and a left rod pivoted to said front connecting member; padded arcuate members connected to the free ends of said right and left rods and engaging the ball of the shoulder and under the arm; adjustable straps connecting the free ends of said arcuate members; right and left shoulder straps connected respectively to said right and left rods; a back cross strap adjustably connecting the upper ends of said arcuate members; and a connecting unit comprising a triangular ring, a strap having a buckle at each end connected to one side of said ring and cooperating with said shoulder straps, and straps with buckles secured to the other sides of said ring to cooperate with the respective ends of said chest strap.
